CONNECTOR FOR COAXIAL CABLE

Charles McDonald Puckette, Jr., Ridgewood, N. J.,
assignor to Allen B. Du Mont Laboratories, Inc.,
Passaic, N. J., a corporation of Delaware

Application March 23, 1945, Serial No. 584,274

7 Claims. (Cl. 174—19)

1

This invention relates to a device by which one or more wires may be easily and quickly attached to the central and outer conductors, respectively, of a coaxial cable connector.

In carrying out the invention one of the wires is connected to a binding post which is provided with a stud that extends into a tubular male contact member to which it may be soldered and which is the inner member of the connector. The wire which is to be grounded may be connected to a sleeve that may be grounded by installing the device.

The invention may be understood from the description in connection with the accompanying drawing, in which:

Fig. 1 is a longitudinal section through a socket and part of a metal chassis wall to which it is connected; and

Fig. 2 is a longitudinal section through the device.

Although this invention is suitable for connecting two wires or a pair of wires to a connector for a coaxial cable, it will be specifically shown and described with the cable connector connected to the inner and outer wires of a coaxial cable. From this it will be obvious that the connector can be connected to other pairs of wires.

In the drawing, reference character 1 indicates a coaxial cable that may, for example, be connected to the connector of this invention. This cable 1 is made up of insulating material containing a center lead 2 and the stranded cylindrical lead 3 which is twisted as indicated at 4 after a portion of the insulation material has been removed at the end of the cable 1.

Reference character 5 indicates a portion of a wall of a cabinet in which a device is located that is provided with a terminal 6 into which the center lead of the coaxial cable is to be electrically connected. The wall 5 may be grounded in any convenient way. A metal socket 7 is attached to this wall by screws 8 passing through the flange of the socket. A sleeve 9 of insulating material is located inside of the socket 7. The parts just described are old and well known.

A metal shell or sleeve 10 that is knurled at one end, as indicated at 11, and is threaded on the inside of that end, as indicated at 12, has an internally extending rim 13 at its other end. A hollow metal disc or washer 14 is placed at the end of the shell 10 when two separate wires are to be connected to the connector. A disc 15 of insulating material of the same diameter as the shell 10 and washer 14 has an annular extension

16 with a thick metal disc 17 anchored in the end thereof.

A metal binding post 20 has a reduced inner end portion 21 and a threaded outer enlarged portion 22 terminating in an outer disc or head 23. A thumbpiece or button 24 of rigid insulating material is provided with an internally threaded nut 25 which is firmly secured therein and fits the threaded portion 22 of the binding post 20.

10 A metal tube or sleeve 27 having an enlarged end portion 28 with sharpened lugs 28' along its outer edge is located coaxially with the binding post 20. The enlarged end portion 28 has an annular inwardly extending rib 29 which extends 15 into a corresponding groove 30 in the solid cylinder 31 of insulating material so that this cylinder is securely anchored in place in the portion 28.

20 A metal tube 32 is provided into which the end 21 of the binding post 20 extends and is securely attached or fastened both electrically and mechanically to this binding post by solder 33.

The inner end of the tube 27 is enlarged and thickened as indicated at 34 and is externally threaded as indicated at 34' to fit the threads 12. A cylindrical extension 35 is provided on the thickened portion 34 and has spaced lugs 36 that extend through holes 14' in disc 14 and into holes 15' in the disc 15 to prevent relative rotation 30 of these parts.

A threaded integral, radial extension 37 is provided on the shell 10 to serve as a binding post upon which the button 38 of insulating material is mounted when two leads are to be connected 35 to this connector.

The operation is as follows:

The tube 27 is introduced into the shell 10 by screwing the external threads 34' through the internal threads 12, and then moving the tube 27 to the position shown in Fig. 2 with the lugs 36 extending through the holes 14' in disc 14 and into holes 15' in disc 15. Good electrical contact is made between tube 27 and disc 14 when this disc is present in the device.

45 The binding post 20 is inserted so that the end portion 21 extends through the metal tube 32 and this end portion is soldered in place as shown at 33. This keeps the binding post 20, tube 32, cylinder 31, tube 27, disc 14 when present, disc 15 and disc 17 from turning or moving axially with respect to one another, but leaves the shell 10 free to move on the cylindrical portion 35.

For example, when a coaxial cable is to be connected to this connector, the insulation is removed 55 from the end of the cable 1 exposing the leads 2

and 3 and the fine wires of lead 3 are twisted together to form lead 4, and the leads 2 and 4 are kept from contacting in any convenient way. Lead 2 is wrapped around binding post 20 and nut 28 is screwed up to clamp the wire 2. Lead 4 is wrapped around the metal of the other binding post 34 when a second or ground wire is used and the button 38 is screwed up.

The shell 10 is brought up to the socket 7 and turned by grasping the knurled portion 11, thus screwing the threaded portion 12 upon the outer threaded portion of this socket 7 and making contact between the lead 4 and socket 7 through extension 31, disc 14 and tube 10. The rim 13 bearing against the enlarged end 34 of tube 27 carries the cylinder 31, tube 32 and binding post 20 to the left to make contact between tube 32 and center terminal 6.

What is claimed is:

1. A connector for a coaxial cable which comprises electrically connected and mechanically separated coaxial sleeves and a binding post extending through both of said sleeves axially thereof, a metal disc in contact with both of said sleeves, one of said sleeves having an externally threaded portion and the other one an internally threaded portion adapted to engage said externally threaded portion.

2. An electrical connector comprising a shell having an internally threaded portion near one end thereof and an inwardly extending rim at the other end thereof, a tube in said shell having an externally enlarged threaded portion thereon adapted to engage said internally threaded portion, said shell extending axially of and being revolvable on said tube, and a binding post rigidly attached to said tube and extending entirely therethrough.

3. An electrical connector comprising a shell having an internally threaded portion near one end thereof and an inwardly extending rim at the other end thereof, a tube in said shell having an externally enlarged threaded portion thereon adapted to engage said internally threaded portion, said shell extending axially of and being revolvable on said tube, a binding post rigidly attached to said tube and extending entirely therethrough and another binding post electrically connected to said shell.

4. An electrical connector comprising a shell having an internally threaded portion near one end and an inwardly extending rim at the other end thereof, an externally threaded socket for engagement by said internally threaded portion, a tube in said shell having an externally enlarged threaded portion thereon adapted to engage said internal threaded portion, said shell extending axially of and being revolvable on said tube, and a binding post rigidly attached to said tube and extending entirely therethrough.

5. An electrical connector, comprising a binding post having two separated smooth portions and two separated threaded portions, insulating material fixed on said binding post, a metal sleeve around said binding post, means to prevent relative rotation between said sleeve and said insulating material, a metal sleeve around said first named metal sleeve, a metal disc between the main portion of said sleeve and said insulating material and a different binding post connected to said disc.

6. The device of claim 5 in which a projection on the upper end of said first named metal sleeve extends axially of it.

7. The device of claim 5 in which a metal disc to support a binding post is provided between the major portion of said first named sleeve and said insulating material, and a projection on said first named sleeve that extends into said disc to provide electrical contact with said disc.
